UNITED STATES PATENT OFFICE.

HARRY P. FAIRCHILD, OF NEW YORK, N. Y.

DESIGN FOR A HANDLE FOR BUTTON-HOOKS, &c.

SPECIFICATION forming part of Design No. 21,403, dated March 15, 1892.

Application filed February 18, 1892. Serial No. 422,037. Term of patent 3½ years.

To all whom it may concern:

Be it known that I, HARRY P. FAIRCHILD, a citizen of the United States, residing at New York, in the county of New York and State of New York, have invented a certain new Design for a Handle, of which the following is a specification.

My invention consists of a new design for a handle for cutlery, button-hooks, and similar articles.

The design is shown clearly in the accompanying drawing, to which reference is made for a complete illustration of the same.

In the drawing the handle is shown applied to a button-hook; but it is obvious that the design may be applied to handles for cutlery or to any similar article requiring a handle.

What I claim is—

The design for a handle, as herein shown and described.

In witness whereof I hereunto set my hand in the presence of two witnesses.

HARRY P. FAIRCHILD.

Witnesses:

L. FRED HURD,
HENRY BARR.
